UNITED STATES PATENT OFFICE.

ELLIS EDGAR HOWSON, OF SALT LAKE CITY, UTAH.

PROCESS OF EXTRACTING SOLIDS.

1,284,346.

Specification of Letters Patent. Patented Nov. 12, 1918.

Application filed October 5, 1917. Serial No. 194,930.

To all whom it may concern:

Be it known that I, ELLIS EDGAR Howson, a citizen of the United States, and a resident of Salt Lake City, in the county of Salt

5 Lake and State of Utah, have invented a new and Improved Process of Extracting Solids, of which the following is a full, clear, and exact description.

This invention relates to an improved

10 method of filtering, whereby solids are extracted from a suspending liquid in a manner to provide mechanically a continuity of operation from the beginning to the end.

The object in view is to provide a filtering 15 process with successive steps arranged in such a manner as to permit of a continuous operation while portions of a solid and suspending liquid will be passing through different and successive steps.

20 Another object in view is to provide the steps of a process whereby a continuous inflow of material may be had and a continuous outflow of the filtered or extracted matter may be had, while successive and progressive steps in the filtration may take place 25 between the inflow and outflow.

In carrying out the objects of the invention different means may be utilized, but for the purpose of illustration a particular construction has been shown in the accompanying drawings, in which—

Figure 1 is a longitudinal vertical section through Fig. 2 on line 1—1.

Fig. 2 is a section through Fig. 1 on line 35 2—2.

Fig. 3 is a section through Fig. 1 on line 3—3.

Fig. 4 is a fragmentary side elevation of 40 part of the structure shown in Fig. 1, one of the filtering members being shown tilted.

Fig. 5 is a detail fragmentary sectional view showing part of one of the filtering members in a tilted position.

Fig. 6 is an enlarged detail fragmentary 45 sectional view through Fig. 2 on line 6—6.

Fig. 7 is a top plan view of a valve disclosing certain features of the invention.

Fig. 8 is a sectional view through Fig. 7 on line 8—8.

50 Fig. 9 is a horizontal sectional view through Fig. 8 on line 9—9.

Fig. 10 is a horizontal sectional view through Fig. 8 on line 10—10.

Fig. 11 is a view similar to Fig. 10 but 55 showing a slightly modified form of valve.

In order that the process may be clearly

understood and the various successive steps understood, a description will be given of the particular structure shown, but it is of course understood that other constructions may be 60 used without departing from the spirit of the invention provided the same will permit of the continuous inflow and outflow and successive steps for separating the material between the inflow and outflow. 65

Referring to the accompanying drawings by numerals, 1 indicates a foundation or platform which is fixed or stationary and is provided, as shown in Fig. 1, with upright walls 2 and 3, said walls extending in circles 70 as shown in Fig. 3 so as to accommodate the circular conveyer 4. A discharge opening 5 is provided at a convenient point in the platform 1 so that the matter discharged between the walls 2 and 3 may be moved by 75 conveyer 4 to the discharge point and from thence disposed of as may be desired. The conveyer 4 is made up of a number of boards or webs 6 secured to the bars 7, said webs acting as blades for moving the material 80 around to the discharge opening 5. A plurality of bracing members 8 connect the bars 7 so that the entire structure will move together and be braced so as to resist any extra strain at any particular point. Each of the 85 bars 7 at the outer end has a grooved wall 9 mounted thereon running on a track 10, whereby the parts are supported at the outer edge while the inner edge is supported by the various gear wheels 11 meshing with the 90 rack 12, which rack is rigidly secured to the bars 7. One of the gear wheels 11 is connected with a shaft 13, which shaft carries a second gear wheel 14 over which a chain 15 passes, said chain also passing over a sprocket 95 wheel 16 rigidly secured to shaft 17. Shaft 17, as shown in Fig. 1, is designed to convey power from any suitable source to chain 15 and to the beveled gear 18 which meshes with gear 19 so as to rotate the standard 20 100 to which it is rigidly secured, said standard being guided and held in proper place by bearings 21 and 22.

As described, the conveyer 4 is intended to remove the unnecessary and undesired 105 solids which are discharged from the various filtering sections 23, which filtering sections are successively dumped, as shown in Figs. 1 and 4. In the drawings a certain number of filtering sections 23 have been shown, but 110 it is evident that a larger or less number may be used without departing from the

spirit of the invention, said filtering sections remaining in the same relative position but being successively dumped by mechanism hereinafter fully described, and successively supplied with the solution to be filtered, said solution being supplied through the pipes 24 and 25. The idea in this connection is to supply one or more kinds of solution to be filtered and to supply the same in a continuous stream, but to intermittently act on the filtering sections 23 so that during the rotation of the supply pipes 24 and 25 the various filtering sections 23 will be in different stages of operation, each filtering section 15 completing the entire cycle of operation on each rotation of the pipe 24. The matter filtered may be any solid in suspension from which the suspending liquid is to be extracted and possibly some of the solid remaining to be submerged again and filtered before discharged from the filtering device.

As shown in Figs. 1 and 2, the supply pipes 24 and 25 are connected to the rotating tanks 26 and 27, respectively, said tanks being preferably rigidly secured to shaft 20 so as to rotate therewith. Pipes 28 and 29 supply different solutions to the tanks 26 and 27, said pipes being stationary and disconnected from the tanks so that the tanks may 30 freely rotate and distribute the solution or the matter in suspension as the pipes rotate. The upper edge of the tank 26 is turned over at 30 and fits into a trough 31 so as to receive any matter spilled therefrom, said overflow 35 being led to a suitable discharge point through pipe 32. As will be evident, when the device is started the solution from pipe 24 is discharged continuously as the same rotates, whereby the various filtering sections 23 are successively supplied with the solids in suspension and also with a solution from pipe 25 which may be any suitable solid in suspension or may be water or any other fluid. The reason that the pipes 24 40 and 25 are spaced at such a great distance apart is to allow the filter to act on the matter discharged from pipe 24 before the matter discharged from pipe 25 is supplied to the respective filtering sections.

50 Each of the filtering sections 23 is supplied with a solid bottom 33 (Fig. 6) having suitable side walls 34 at the sides and ends, to which may be secured a filtering substance 35 consisting of a wire or coarse mesh member 36 and a fine mesh or cloth member 37. Suitable supporting sleeves 38 are provided and held in place by bolts 39 so as to support the filtering medium 35 properly when the matter to be filtered has been discharged 55 thereon. On each of the filtering sections 23 is arranged an overhanging member 40 which prevents any spilling of the material between the filters, as the matter discharged on any of the members 40 will gravitate into 60 the next adjacent filter and be properly

acted on thereby. As shown in Figs. 1 and 6, a plurality of cleats 41 are secured to the bottom 33 of the various filtering sections 23 so as to clamp the bars 42 in position, said bars being rigidly secured to shaft 43, which 70 shaft is supported in suitable journal members 44 and 45 on upright members 46 and 47. A spring 48 bears against the outer bar 42 and against the bearing 45 so as to continually urge the filter 23 radially inwardly. 75 This action is to cause the jarring of the entire filter 23 under certain circumstances, as hereinafter described, so as to shake out any of the solids remaining on the filtering section 23 when the filter has been turned, as 80 shown in Figs. 1 and 4. As shown in Figs. 1 and 2, a cap 49 is mounted on the end of each of the shafts 43 for reducing the friction between said shafts and the jarring cams 50 and 51 mounted on the tubular member or wall 52. It will be observed that the tubular member or wall 52 is rigidly secured to the shaft 20 and also is rigidly secured to a ring 53 carrying the rack 54, which rack is mounted on suitable pinions 55 whereby 85 said rack is properly supported. As shown in Fig. 2, there is provided one large jarring member 50 and a number of small jarring members 51, together with a double face cam 56.

90 When the member 52 and associated parts are moving in the direction of the arrow 57, as shown in Fig. 2, a small jarring cam 51 will engage the various caps 49 and will give the filtering sections 23 a short outward movement, and by reason of the spring 48 the filters will be given a quick inward movement until the caps strike the member 52, thus producing a slight jar in order that the matter being filtered may be jarred or 95 shaken so as to allow a better filtering action. When a filtering section 23 reaches the large cam 50 it is moved outwardly by the cam and then quickly inwardly by the spring 48 so as to be given a considerable jar. This 100 jar occurs when the filter has been tilted to the position shown in Figs. 1 and 4, whereby the old solid matter left on the filter will be jarred off and caused to fall on to the conveyor 4.

105 In order that the various filters 23 may be turned or tilted as shown in Figs. 1 and 5 at the proper time, a tilting pin 58 enters the notch 59 of lever 60, as shown in Figs. 4 and 5, thus causing said lever to be rotated 110 as the pin is moved along. The rotation for a distance of approximately 45° will turn the filter 23 a corresponding distance by reason of the fact that the lever 63 is rigidly secured to shaft 43 and, consequently, the 115 shaft and filter turn with the lever. This turning operation is approximately completed at the time the cap 49 slips off the large cam 50. The particular filter 23 which has been tilted remains in a tilted 120 125

position until the double cam 46 strikes the cap 49 and again moves the same outwardly against the action of spring 48, said movement continuing until the projecting ends 5 of the bars 42 come in alinement with the notches 61 in the supporting bars 62 and then the upper notch 63 of lever 60 will engage the re-tilting pin 64, and as this pin moves with member 62 the filter will be 10 again moved to its horizontal position. After the pin has moved to its horizontal position the cap 49 gradually slides off the end of cam 56 and, consequently, the filter is returned to its original position without a 15 jar and the extending ends of the bars 42 are moved out of registry with the notches 61, whereupon the supporting bar 62 acts as a support for that side of the filter while the overhanging member 40 overlaps the next 20 adjacent filter. In this way each of the filters 23 is shaken a number of times by the small cams 51 and given one large jar by the cam 50 as the tubular member or drum 52 rotates. In addition, each of the filters 23 25 is tilted by the pins 58 and 64, respectively, so as to dispose of or discharge the solid matter into the space between the walls 2 and 3 whereby the conveyer 4 may move the same to the discharge point 5.

30 After the pipes 24 and 25, respectively, have discharged certain matter into the respective filters, the liquid and part of the solids are extracted therefrom by suction, said suction beginning immediately after 35 the discharge of the matter into the filters or during the discharge thereof, and automatically coming into operation and moving out of operation by reason of a plurality of arms 65 properly positioned on the ring 40 53 or the rack 54 and moved thereby so as to operate the various valves 66 in proper timed relationship to the operation of the pipes 24 and 25 and the tilting of the filters 23. It will be noted that there is one valve 45 66 for each of the filters 23 and that these valves are all connected to pipes 67, 68, 69 and 70.

Immediately after the pipe 24 has supplied solution to the filter 23 the valve connected 50 therewith is turned by one of the arms 65 so that the vacuum pipe 70 will be turned on and the liquid part of the solution will be sucked through pipe 70 to a discharge point, said liquid carrying with it some of the solids or only liquid matter, according 55 to the fineness of the filtering medium on the filter. After this has been carried on for a predetermined length of time the next arm 65 will strike the valve and move the same 60 a predetermined distance, whereupon the passageway to the second vacuum pipe 69 is opened. Simultaneously with connecting pipe 69 with the filter or previous thereto, a quantity of submerging fluid is discharged 65 by pipe 25 so that this submerging fluid is

removed through the vacuum pipe 69 and with it certain of the solids, as the case may be. Pipe 69 is connected with the filter for a less time than the pipe 70. At a predetermined time the pipe 69 is cut off by 70 another arm 65 operating the valve 66, whereupon not only will pipe 69 be cut off but a pipe 68 connected to the filter for supplying a stirring and mixing medium, as for instance, air or water, will be turned on or 75 connected for supplying air or water a short time to the filter. After the air or water has been supplied for a predetermined time, a fourth arm engages the valve 66 and operates the same for turning off pipe 68 and so turning on pipe 67, said last mentioned pipe being a drainage pipe so as to drain off the water or to allow the air to circulate in case air is being used. This last operation occurs approximately at the time the filter is 85 tilted and may occur just before or after or during the tilting operation. In order that the pipes 67 to 70 may communicate through the various valves 66 to the various filters 23, a pipe 71 is connected to the bottom of 90 each filter, as shown in Fig. 6, and to the respective valves 66, there being one pipe 70 and one valve 66 for each filter, these members remaining stationary except for the tilting operation of the filters and the 95 movement of the valve, plug and associated parts in the valves. It is of course understood that a fifth arm 65 is provided for turning off the pipe 67 so that the valve 66 will be closed.

100 The detail construction of the valve 66 may be varied in a number of particulars provided the same accomplishes the results above mentioned. A preferable construction of valve is shown in Figs. 7 to 10, inclusive, 105 in which there is provided a central master plug 72 connected with the pipe 71, said plug having a central passageway 73 merging into a radiating passageway 74 adapted to register at different times with the passageways 110 75, 76, 77 and 78. Associated with the master plug 72 are auxiliary plugs 79, 80, 81 and 82 formed with vertical passageways, as shown in Fig. 8, merging into radial passageways adapted to register at different times with 115 the passageways 75 to 78, inclusive. The plugs 79 to 82, inclusive, are connected to the respective pipes 67 to 70, inclusive, so that any of the pipes 67, 68, 69 or 70 may be caused to communicate with pipe 71. The 120 master plug 72 is provided with a centrally arranged gear 83 (Fig. 8) which meshes with the gears 84, 85, 86 and 87 connected with the auxiliary plugs, whereby when the master plug is turned a predetermined distance the auxiliary plugs will be turned the same distance, whereby the proper passageways may be brought into registry. The 125 fifth arm 65 above mentioned is intended to move the arms 88 of the operating plate 89 a 130

proper distance for shifting the last plug and associated plugs for preventing a communication of any of the auxiliary plugs with the master plug.

5 In Fig. 11 will be seen a view similar to Fig. 10, showing a slightly modified form of the invention in which there are provided five auxiliary plugs 90 instead of four auxiliary plugs, as shown in Fig. 10. This arrangement is provided where it is desirable to have another pipe or tube for drawing off certain of the liquid matter.

In operation, the power shaft 17 is started and as soon as the same, together with the 15 parts connected thereto, has attained the speed desired the matter in suspension is discharged into the tanks 26 and 27 and is allowed to flow therefrom through pipes 24 and 25 so as to supply the various filters 23 with proper quantities of the matter in suspension. Preferably the pipe 35 is turned off until it has reached the particular filter first supplied with the matter in suspension from pipe 24, whereupon it is turned on and 25 left turned on as long as the device is in operation. The pipes 24 and 25 are continually rotated at a predetermined speed without any stops in order to successively supply the matter to be filtered to the various filters 23. 30 The filters 23 are successively tilted and re-tilted after having gone through the previous steps in the process of filtration.

It will be noted from Fig. 2 that in case an excessive quantity of material is supplied to 35 any particular filter said excessive material may flow out the overflow chute 91 into an annular trough 92 which has a suitable discharge (not shown) for leading the overflow to a convenient discharge point. In this 40 way an ample quantity is assured for the respective filters while none of the material is wasted, as it may be again forced through pipes 28 and 29 to tanks 26 and 27. This is especially true as the overlapping members 45 40 prevent any spilling between the filters, and any slight spilling on the inner end of the filters is directed by the deflector 93 into the conveyer 4 and is moved from thence to the discharge point 5. As the material is 50 constantly supplied and moved at a uniform rate the resulting filtration or extraction is constant and of a given quantity per

unit of time, so that an easy estimate may be made of the output of any particular device and, consequently, the cost of filtering any 55 given quantity of material. It is to be noted that the above described construction may be used in extracting or separating solids in a pulverized condition from a suspending liquid regardless of the particular solid or 60 particular suspending liquid.

The apparatus whereby I may carry out the method herein set forth forms the subject matter of pending application, Serial No. 194,929.

65

What I claim is:

1. The method herein described of extracting solids held in suspension in a liquid, consisting in subjecting a series of filters to an intermittent jarring action, delivering the material successively to the filters, drawing off the liquid, delivering a submerging liquid successively to the filters from which the liquid has been removed, drawing off the liquid, admitting a stirring 75 and mixing fluid to the material, and allowing the fluid to escape.

2. The method herein described of extracting solids held in suspension in a liquid, consisting in subjecting a series of filters to an intermittent jarring action, delivering the material successively to the filters, sucking off the liquid, delivering a submerging liquid successively to the filters from which the liquid has been removed, sucking 85 off the liquids, admitting a stirring and mixing fluid to the material, and draining off the liquid.

3. The method herein described of extracting solids held in suspension in a liquid, consisting in subjecting a series of filters to an intermittent jarring action to facilitate the filtering action, delivering the material successively to the filters, sucking off the liquid, delivering a submerging liquid successively to the filters from which the liquid has been drawn off, sucking off the liquid, admitting a stirring and mixing fluid into the material through the bottom of the filter, draining off the liquid, successively tilting the filters, and subjecting the tilted filters to a jarring action to jar off the material adhering to the filter.
